UNITED STATES PATENT OFFICE

THOMAS J. FLEMING, OF WATERBURY, CONNECTICUT

APPARATUS FOR CONSTRUCTION

Application filed December 22, 1930. Serial No. 504,174.

This invention relates to a method of and apparatus for construction.

In certain construction operations, for example, in the laying of concrete roadway, pavements, and the like, the operations of proportioning, mixing and laying the materials are interdependent. Consequently, a break-down in one of the operations or of the apparatus performing an individual operation results in disruption of the other operations. Thus, where materials are proportioned and mixed at a central plant utilizing generally unitary or dependent apparatus, a break-down of either the proportioning or the mixing apparatus causes the work of construction to be impeded or stopped for a material length of time.

Accordingly, an object of my invention is the provision of a useful construction by which hitherto interdependent operations are carried on independently, to the end that a break-down in one operation need not interrupt the progress of the work under construction. A further object is the provision of apparatus for handling and/or transporting the construction materials treated in the various operations, by which the said operations may be carried on independently of each other. A further object is the provision of an improved article in the nature of a container in which suitably proportioned material such as aggregate may be transported in dry batches to a mixing plant located at the place of construction. A further object is the provision of a material container of the above character which may be readily filled, handled, and dumped, and in which materials may be advantageously stored until needed. A further object is to provide a material container so constructed that when dropped it will not break or bend out of shape permanently. A further object is to provide a container which, when empty, may be easily handled without the use of mechanical devices.

Further objects and advantages will be in part obvious and in part indicated from the following analysis of the invention, it being understood, however, that various changes may be made therein by those skilled in the

art without departing from the scope and spirit of this invention.

In the drawings—

Fig. 1 is a schematic representation of a proportioning plant delivering to a container in accordance with my invention;

Fig. 2 is a schematic representation of the container being unloaded at the mixing plant located preferably at the locus of the construction work being carried on;

Fig. 3 is a view of the untied fabric cylinder or envelope from which my improved material container is formed;

Fig. 4 is a detail of a neck block and associated holding cable;

Fig. 5 is a detail in section illustrating the mode or securement of the tying ropes to the cylinder or envelope.

Referring to the drawings, and particularly to Fig. 1, the reference character 10 designates generally a proportioning plant wherein materials, such as aggregate, from batch boxes 11 and 12 are suitably proportioned and delivered through a discharge spout 13. Adjacent the proportioning plant 10, I arrange a suitable track 14 with which cooperates a movable trolley 15 from which depends a carrying hook 16.

A container hereinafter referred to as a batch bag, and designated as at 20, is provided with lifting eyes 21, 22, one of which cooperates with the hook 16. The bag 20 may be suspended adjacent the proportioning apparatus 10 so that the delivering spout 13 enters the batch bag through a suitable opening 24, and the proportioned materials are consequently delivered into the bag.

When the bag has been filled, it may be moved along the track 14 and released from the hook 16, preferably by means of a trip mechanism generally designated at 25 and operated, for example, by a cord or wire 26. It is proposed that the bags 20 when released from the hook 16 are dropped on to a truck in which they are hauled to the road under construction and dumped in front of a mixer generally designated at 30, Fig. 2. When needed, a bag may be moved or picked up by a derrick or equivalent means diagrammatically shown as at 31 and moved to a po-

sition above the mixing plant 30. When the bag is dumped, the proportioned materials discharged from the bag fall into the mixer 30. When empty, the bag is released from the derrick hook 32 by suitable trip mechanism 33 and dropped on a truck and thereupon hauled back to the proportioning plant to be filled again.

It is generally desirable to store a plurality of the filled bags adjacent the mixing plant 30. Such arrangement is advantageous in storing up materials so that the mixer may continue in operation in case of a break-down in the proportioning or hauling operations.

Referring to Figs. 3, 4 and 5 wherein the construction details of the batch bag are illustrated, the bag 20 is constituted by a heavy fabric cylinder or tube, preferably of canvas of a strength depending on the weight of the materials to be carried. For extra heavy weights, the canvas cylinder may be reinforced with ropes or rope webbing.

Disposed intermediate the ends of the cylinder is the opening 24, above referred to, which is provided with an interior flap 35 shaped somewhat like the frustum of a cone. The materials from the proportioning plant are thus fed through the flap 35 which functions, upon withdrawal of the spout 13, to prevent the materials contained within the bag from escaping when the bags are dumped on and off the hauling trucks.

The fabric cylinder is gathered to form a closure adjacent both ends by tie ropes 36, the said ropes being attached to the bags by securing the same about bolts 37 (Fig. 5) passing through the bag fabric and protected as by steel washers 38 which are preferably disposed on both the inside and outer surface of the fabric. A large, heavy canvas belt washer 40 is disposed between the bag fabric and the outer steel washer 38, the end of the rope being wound between the said washer 40 and bag fabric for securing the same when the bag is closed.

Neck blocks 42, which may be of wood, are provided, one for each end of the bag, the said blocks having a central portion 43 of reduced diameter and end portions 44, 45 of greater diameter. All corners of the block are preferably rounded, whereby wear of the fabric is lessened. Each block is centrally bored as at 46 for the reception of a rope or cable bent and secured to form the eyes 21, 22 aforesaid and the inside eyes or loops 21a, 22a. By reference to Fig. 1, it will be seen that the fabric is gathered about the blocks 42 with the tying ropes 36 seating in the annular space about the reduced portion 43 of said blocks; consequently the fabric is securely joined to the block until positively released therefrom by untying the ropes 36. A connecting rope 47 extends between the blocks at both ends of the bag so that when the bag is opened at one end, the block at the

open end will be held from falling, the rope 47 being provided with end loops 48 cooperating with the loops or eyes 21a and 22a. It will thus be obvious that the bag may be lifted from either end and emptied from the opposite end, the provision of the lifting eyes 21, 22 at both ends of the bag making always available a ready hoisting connection, no matter in what position the bag falls when dumped from the truck.

By referring to Fig. 2, it will be seen that the bag may be dumped by releasing the relatively lower tying rope 36 from the holding washer 40, the gathers of the bag at the dumping end being released by the weight of the material being discharged.

By reference to Fig. 4, it will be seen that the neck blocks 42 which, when the bag is in closed or tied relation, engage against the gathered neck of the bag, and that the lifting stresses are transmitted throughout the fabric body to thus increase the wear of the bag. In other words, the lifting ropes in no manner pass through the fabric of the cylinder or envelope, and the stresses are resulting not localized at points of attachment between the lifting ropes and bag fabric as has hitherto been proposed.

It will be appreciated that other equivalent means might be substituted for gathering or tying the bag and for supporting the same from the holding ropes, and all such equivalent arrangements are included within the scope of the present invention.

It will be seen that the several objects of the invention are achieved and other advantageous results attained. As many changes could be made in carrying out the above invention, without departing from the scope thereof, it is intended that all matter contained in the above description shall be interpreted as illustrative and not in a limiting sense.

I claim:

1. A batch bag comprising, in combination, a tubular fabric element, releasable closure means therefor, and means at one end thereof of whereby the bag may be lifted from one end and dumped from its other end.

2. A batch bag comprising, in combination, a tubular fabric element, releasable closure means adjacent the ends thereof, and means at one end thereof whereby the bag may be lifted from one end and dumped from its other end.

3. A batch bag comprising, in combination, a tubular fabric element, releasable closure means adjacent the ends thereof, and means extending from each end of the element whereby the bags may be lifted from either end and dumped from its other end.

4. A batch bag comprising, in combination, a tubular fabric element, releasable closure means adjacent the ends thereof, and means extending through and beyond the ends of the

element whereby the bags may be lifted from either end and dumped from its other end.

5. A batch bag comprising, in combination, a tubular fabric element, releasable closure means adjacent the ends thereof, and lifting eyes extending from the ends of the element, and connected interiorly of said element.

6. A batch bag comprising, in combination, a tubular fabric element, releasable closure means adjacent the ends thereof, and lifting means at one end of the bag comprising a member disposed interiorly of and cooperating with an end closure, and a lifting rope operatively related to said member.

15 7. A batch bag comprising, in combination, a tubular fabric element, releasable closure means adjacent the ends thereof, and lifting means disposed at both ends of the bag, said lifting means including neck blocks 20 arranged interiorly of the bag and cooperating with the closure means, lifting ropes operatively related to said neck blocks, and a connection between said neck blocks.

25 8. A batch bag comprising, in combination, a tubular fabric element, releasable closure means adjacent the ends thereof, and lifting means disposed at both ends of the bag, said lifting means comprising neck blocks cooperating with the closure means, a tie rope extending between said neck blocks, and lifting eyes having a connection with said neck blocks.

35 9. A batch bag comprising, in combination, a tubular element, closure ropes disposed adjacent the ends thereof, the element being gathered and so held by said ropes, neck blocks within said element adjacent the gathered portions thereof, and lifting ropes secured to said neck blocks and extending exteriorly 40 of the closures.

45 10. A batch bag comprising, in combination, a tubular element, closure ropes disposed adjacent the ends thereof, the element being gathered and so held by said ropes, neck blocks within said element adjacent the gathered portions thereof, lifting ropes secured to said neck blocks and extending exteriorly of the closures, and a tie rope connecting said blocks.

50 11. A batch bag comprising, in combination, a container element of flexible material throughout having open ends, closure means for said open ends, and lifting means associated with one of said closure means, whereby the container may be lifted by said lifting means and dumped from its other end.

60 12. A batch bag comprising, in combination, a container element of flexible material throughout having open ends, releasable closure means for said open ends, and lifting means at the ends of said element and operatively related to said closure means.

65 13. A batch bag comprising, in combination, a container element of flexible material throughout having open ends, releasable clo-

sure means for said open ends, and lifting means extending through said element and operatively related to said closure means.

Signed at Waterbury, Connecticut, this 5th day of December, 1930.
